UNITED STATES PATENT OFFICE.

WILLIAM R. JEAVONS, OF CLEVELAND, OHIO.

DESIGN FOR A WINDOW-FRAME FOR STOVE-DRUMS.

44,206.

Specification for Design.

Patented June 17, 1913.

Application filed April 10, 1913. Serial No. 760,318. Term of patent 14 years.

To all whom it may concern:

Be it known that I, WILLIAM R. JEAVONS, a citizen of the United States, residing at Cleveland, in the county of Cuyahoga and State of Ohio, have invented a new, original, and ornamental Design for Window-Frames for Stove-Drums, of which the following is a specification, reference being had to the accompanying drawing, forming part hereof, wherein—

Figure 1 represents a front elevation and Fig. 2 a central longitudinal sectional view of the frame exhibiting my new design.

I claim:

The ornamental design for a window-frame for stove drums, as shown.

WILLIAM R. JEAVONS.

Witnesses:

JOHN B. HULL,
ARNOLD R. WHITTAKER.
